(57) CLAIM

The ornamental design for a tape measure, as shown and described.

DESCRIPTION

FIG. 1 is a perspective view of the front and right-hand side of a tape measure showing my new design;

FIG. 2 is a perspective view of the rear and left-hand side of a tape measure showing my new design;

FIG. 3 is a right side elevational view of FIG. 1;

FIG. 4 is a front elevational view thereof;

FIG. 5 is a top view thereof;

FIG. 6 is a left side elevation showing the opposite side of FIG. 3;

FIG. 7 is a rear elevational view thereof; and,

FIG. 8 is bottom view thereof.

The broken line showing is for illustrative purposes only and forms no part of the claimed design.
